CLAIM

The ornamental design for a pen housing, as shown and described.

DESCRIPTION

FIG. 1 is a perspective view of a pen housing, showing one embodiment of our new design;
FIG. 2 is a top plan view thereof;
FIG. 3 is a bottom plan view thereof;
FIG. 4 is a front elevational view thereof, the rear elevational and top elevational and bottom elevational views being identical;
FIG. 5 is a perspective view of a pen housing, showing another embodiment of our new design;
FIG. 6 is a top plan view thereof;
FIG. 7 is a bottom plan view thereof; and,
FIG. 8 is a front elevational view thereof, the rear elevational, top elevational and bottom elevational views being identical.
